CLAIM

The ornamental design for the dog slide, as shown and described.

DESCRIPTION

FIG. 1 is a rear perspective view of the dog slide, showing my new design;

FIG. 2 is a top view thereof;

FIG. 3 is a bottom view thereof;

FIG. 4 is a left side view thereof;

FIG. 5 is a right side view thereof;

FIG. 6 is a front view thereof; and,

FIG. 7 is a rear view thereof.

The broken lines in the drawings illustrate the portions of the dog slide, which form no part of the claimed design.
